UNITED STATES PATENT OFFICE

120,209

DESIGN FOR A COMBINED BUMPER, HEAD LAMPS, AND LICENSE PLATE HOLDER

William W. Aché, Los Angeles, Calif.

Application September 20, 1939, Serial No. 87,309

Term of patent 7 years

To all whom it may concern:

Be it known that I, William W. Aché, a citizen of the United States, residing at Los Angeles, in the county of Los Angeles, State of California, have invented a new, original, and ornamental Design for a Combined Bumper, Head Lamps, and License Plate Holder, of which the following is a specification, reference being had to the accompanying drawing, forming part thereof.

Fig. 1 is a front elevational view of a combined bumper, head lamps, and license plate holder, showing my new design; Fig. 2 is a top plan view; Fig. 3 is a section taken on the line 3—3 of Fig. 1; Fig. 4 is an end elevational view thereof; and Fig. 5 is an enlarged perspective view viewing the bumper from the top.

I claim:

The ornamental design for a combined bumper, head lamps, and license plate holder, as shown.

WILLIAM W. ACHÉ.
